[57] ABSTRACT

The disclosure describes a tool for applying putty either to a window in which putty must be formed on all sides of the window frame or to a window in which putty is excluded from one or more sides of the window frame. The tool includes intersecting chamfered surfaces which form putty onto adjacent sides of a window frame corner and includes additional intersecting surfaces which form putty along one side and exclude putty from an adjacent side of a window frame corner.

PUTTY APPLICATION TOOL

BACKGROUND AND SUMMARY OF THE INVENTION

Traditionally, a pane of window glass has been held in place by frame members arranged in a rectangular configuration around the glass. In order to effectively seal the glass to the frame members, a bead of putty has been placed around the perimeter of the glass adjacent all of the frame members. A variety of tools for achieving this purpose have been described in the past. For example, two such tools are shown in U.S. Pat. Nos. 2,247,603 and 2,247,604 (Christman - July 1, 1941). Although putty application tools of this type may be useful in connection with such windows, experience has shown that they cannot be effectively used for more modern types of windows in which putty is excluded from one or more frame members. If conventional putty application tools are used on such a window, excess putty tends to be formed along the frame member from which it must be excluded, thereby necessitating removal of the excess putty by hand. This is a time-consuming operation which generally leaves ragged edges and an undesirable appearance at the corner of the window.

In order to overcome the deficiencies of the prior art, applicant has invented a unique putty application tool which can accommodate windows having a continuous bead of putty or windows having putty excluded from one or more sides of the frame by merely turning the tool upside down. When the bottom surface of the tool is adjacent the glass pane, intersecting chamfered edges form putty along both adjacent sides of a window frame so that a smooth continuous bead is easily formed, even by a novice. Comating surfaces adjacent the chamfered surfaces contact the frame members to prevent putty from extending too far away from the glass pane. By merely reversing the tool so that its top surface is adjacent the glass pane, additional chamfered surfaces intersecting the comating surfaces can be used to form a bead of putty adjacent one frame member while effectively excluding putty from an adjoining frame member adjacent a corner of the window frame. By this unique arrangement of components, the same tool can be used for accommodating any type of puttyed window now commonly found in construction and putty may be applied to the windows with a degree of ease and speed heretofore unattainable.

DESCRIPTION OF THE DRAWINGS

These and other advantages and features of the present invention will hereafter appear in connection with the accompanying drawings wherein like numbers refer to like parts throughout and wherein:

FIG. 1 is an isometric view of a preferred form of putty application tool embodying the invention;

FIG. 2 is a top plan view of the tool shown in FIG. 1;

FIG. 3 is a bottom plan view of the tool shown in FIG. 1;

FIG. 4 is a side elevational view of the tool taken along line 4-4 in FIG. 3;

FIG. 5 is another side elevational view of the tool taken along line 5-5 in FIG. 3;

FIG. 6 illustrates the manner in which the tool is used in connection with a window on which putty is formed on adjacent sides of a window frame;

FIG. 7 illustrates the manner in which the tool is used in connection with a window on which putty is formed on only one of two adjacent frame members;

FIG. 8 illustrates the use of the tool in connection with another corner of the window shown in FIG. 7;

FIG. 9 illustrates the manner in which the tool is used to form a bead of putty along a straight window frame member;

FIG. 10 is a fragmentary, cross-sectional view taken along line 10-10 of FIG. 8; and

FIG. 11 is a fragmentary, cross-sectional view taken along line 11-11 of FIG. 8.

DESCRIPTION OF THE PREFERRED EMBODIMENT

Referring to FIGS. 6-11, a putty tool embodying a preferred form of the invention can be used in connection with a window 1 comprising a glass pane 2 that is supported by an upper frame member 4 having a planar side 5 adjacent and perpendicular to the glass pane. As shown in FIG. 6, the window also comprises a left hand frame member 6 having a planar side 7 perpendicular to the glass pane. Frame members 4 and 6 are arranged perpendicular to each other to form a square corner 8. As shown in FIG. 7, the window also comprises a right hand frame member 9 having a planar side 10 which is perpendicular to glass pane 2. Frame members 4 and 9 are arranged perpendicular to each other to form a square corner 11. Window 1 can also comprise a lower frame member (not shown) which is parallel to upper frame member 4.

As shown in FIGS. 7-11, the window can be constructed so that beads of putty 12 and 13 are located adjacent frame members 6 and 9, respectively, whereas no putty is located adjacent frame member 4. Alternatively, as shown in FIG. 6, the window can be constructed so that beads of putty are located adjacent each of frame members 4, 6 and 9.

Referring to FIGS. 1-5, a preferred form of putty application tool made in accordance with the present invention comprises a planar top surface 16 and a planar bottom surface 18 that is parallel to and spaced $\frac{1}{8}$ inch from surface 16. Planar chamfered surfaces 20 and 22 form identical obtuse angles with respect to bottom surface 18 and intersect to form an edge 24.

Planar comating surfaces 26 and 28 are each perpendicular to surfaces 16 and 18 and intersect at right angles to form a square corner that defines an edge 30 which is perpendicular to surfaces 16 and 18. The lower portions of comating surfaces 26 and 28 define edges 32 and 34 which lie in a median plane 36 that is half way between surfaces 16 and 18.

The tool also defines an upper curved surface 40 that is bounded on its lower side by a peripheral circular edge 42 that lies in median plane 36. The circular edge has a center point 44 that is colinear with edge 30 and has a radius R of 3 $\frac{1}{8}$ inches. Surface 40 intersects with comating surfaces 26 and 28 to form edges 46 and 48, respectively.

Curved surface 40 is bounded on the top by an upper circular edge 50 lying in top surface 16. Edge 50 has a center point colinear with edge 30 and a radius R1 of about 3 11/16 inches.

The tool also defines a lower curved surface 54 that is bounded by peripheral circular edge 42 and by a lower circular edge 56 lying in bottom surface 18. Edge 56 has a center point colinear with edge 30 and a radius R2 equal to about 3 11/16 inches, i.e., equal to R1. Lower curved surface 54 intersects surfaces 20 and 22 to form edges 58 and 60, respectively.

The surfaces are arranged so that a plane T1 tangent to surface 40 at the intersection of surface 40 and surface 26 is parallel to chamfered surface 22. Likewise, a plane T2 tangent to surface 40 at the intersection of surface 40 and surface 28 is parallel to chamfered surface 20. Surface 40 makes an angle of about 118° with respect to top surface 16 and surface 54 also makes an angle of about 118° with respect to bottom surface 18. Chamfered surfaces 20 and 22, likewise, make angles of about 118° with respect to bottom surface 18.

In order to use the putty tool on a window of the type shown in FIG. 6 in which putty is formed adjacent each of the frame members, bottom surface 18 is placed adjacent glass pane 2 and edge 30 is maneuvered into any corner, such as corner 8, so that chamfered surfaces 20 and 22 form a smooth bead of putty adjacent planar sides 5 and 7 of frame members 4 and 6, respectively. It should be noted that comating surfaces 26 and 28 contact and fit flush against planar sides 5 and 7 of frame members 4 and 6, respectively, to prevent putty from extending beyond the upper portion of chamfered surfaces 20 and 22, i.e. beyond edges 32 and 34. Edge 30 of the tool can be maneuvered into each of the other corners of the window frame in order to achieve the same results shown in FIG. 6.

In order to form a bead of putty along a straight portion of frame member, either the top or bottom surfaces can be placed adjacent the glass. Peripheral circular edge 42 is then slid along a frame member, as shown in FIG. 9, so that either surface 40 or 54 smooths the putty into a continuous bead.

In order to place putty on a window frame of the type shown in FIGS. 7 - 11 in which no putty is placed adjacent frame member 4, the tool is used in the manner shown in FIG. 9 with the top surface against the glass until a left-hand corner, such as corner 8, is approached. At this point, the tool is maneuvered into the position shown in FIG. 8 so that comating surface 6 lies flush against planar side 5 of upper frame member 4. The contact between the frame member and comating surface 26 prevents putty from being squeezed adjacent frame member 4.

As shown in FIG. 7, the tool can be reversed to accommodate a right hand corner, such as corner 11, in which comating surface 28 is fitted flush against planar side 5 of upper frame member 4 to prevent putty from extending beyond corner 11 into contact with frame member 4.

Those skilled in the art will recognize that only a single preferred embodiment of the invention has been disclosed herein, and that the embodiment may be altered and modified without departing from the true spirit and scope of the invention as defined in the accompanying claims.

What is claimed is:

1. A tool for applying putty to a window having a glass pane bordered by a first frame member having a first end point and a second end point, a second frame member arranged perpendicular to the first frame member at the first end point to form a first corner and

a third frame member arranged perpendicular to the first frame member at the second end point to form a second corner, said tool comprising:

a planar top surface;

a planar bottom surface parallel to the top surface and displaced from the top surface by a predetermined span;

first means located adjacent to the bottom surface for defining a first chamfered surface and a second chamfered surface intersecting the first chamfered surface to define a first edge adapted to be moved into the first corner while the bottom surface is adjacent the glass pane so that the first and second chamfered surfaces form a bead of putty which bridges between the glass pane and the first and second frame members;

second means for defining a first comating surface located between the first chamfered surface and the top surface and for defining a second comating surface located between the second chamfered surface and the top surface, said first and second comating surfaces being adapted to comate with the first and second frame members across a predetermined width for preventing putty from extending more than a predetermined distance from the glass pane;

third chamfered means for intersecting the first comating surface to form a second edge adapted to be moved into the first corner while the top surface is adjacent the glass pane and the first comating surface is positioned against the first frame member and for forming a bead of putty on the second frame member adjacent the first corner while the contact of the first comating surface with the first frame member prevents putty from extending beyond the first corner into contact with the first frame member; and

fourth chamfered means for intersecting the second comating surface to form a third edge adapted to be moved into the second corner while the top surface is adjacent the glass pane and the second comating surface is positioned against the first frame member and for forming a bead of putty on the third frame member adjacent the second corner while the contact of the second comating surface with the first frame member prevents putty from extending beyond the second corner into contact with the first frame member.

2. A tool, as claimed in claim 1, wherein the first chamfered surface undercuts the first comating surface and wherein the second chamfered surface undercuts the second comating surface when the bottom surface is positioned adjacent the glass pane.

3. A tool, as claimed in claim 1, wherein the first and the second comating surfaces are planar surfaces that intersect at a right angle to form a fourth edge perpendicular to the top surface.

4. A tool, as claimed in claim 3, wherein the first comating surface terminates along a fifth edge between the top and bottom surfaces, wherein the second comating surface terminates along a sixth edge between the top and bottom surfaces and wherein the fifth and sixth edges lie in a median plane parallel to the top surface.

5. A tool, as claimed in claim 4, wherein the third and fourth chamfered means are defined by a curved surface bounded on one side by the first comating surface,

bounded on a second side by the second comating surface, bounded on the bottom by a peripheral circular edge lying in the median plane having a center point colinear with the fourth edge and having a radius with a predetermined length, and bounded on the top by a second circular edge lying in the top surface having a center point colinear with the fourth edge and a radius less than the predetermined length.

6. A tool, as claimed in claim 5, wherein the first and second chamfered surfaces are planar surfaces, wherein a plane tangent to the curved surface at the line of intersection between the curved surface and the first comating surface is parallel to the second chamfered surface and wherein a plane tangent to the curved surface at the line of intersection between the curved

5
10
15

surface and the second comating surface is parallel to the first chamfered surface.

7. A tool, as claimed in claim 6, further comprising a second curved surface bounded on a first side by the first chamfered surface, bounded on a second side by the second chamfered surface, bounded on the top by the circular peripheral edge and bounded on the bottom by a third circular edge lying in the bottom surface having a center point colinear with the fourth edge and having a radius equal to the radius of the second circular edge, whereby the peripheral circular edge can be moved against the first frame member to form a bead of putty irrespective of whether the top or bottom surface is adjacent the glass pane.
